MECHANICAL TIME FUSE

John J. Hart, Bryn Mawr, Pa., assignor to the
United States of America as represented by the
Secretary of War

Application December 15, 1939, Serial No. 309,418

2 Claims. (Cl. 102—83)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to mechanism for releasing the timing disk in a mechanical time fuse from the setting cap after the fuse has been set and at the time a projectile is fired armed with the fuse.

It is an object of the invention to generally simplify and provide a release mechanism more positive in its action than release mechanisms used for such function heretofore in the art.

It is a further object of this invention to provide a timing disk release mechanism operable to release the timing disk by the same force that operates to drive the timing disk whereby release of the timing disk and initiation of the driving thereof will be coordinated in point of time.

The specific nature of the invention as well as other objects and advantages thereof will clearly appear from a description of a preferred embodiment as shown in the accompanying drawings in which:

Fig. 1 is a plan view of the release mechanism of this invention looking from the bottom of the setting cap;

Fig. 2 is a sectional view taken on the line 2—2 of Fig. 1;

Fig. 3 is a sectional view similar to Fig. 2 showing the release mechanism in interlocked relation with the setting cap and timing disk for setting the fuse.

Referring now to the drawings wherein similar elements are identified by similar characters throughout, there is shown in Fig. 2 a fragmentary portion of a fuse sufficient to disclose the present invention. The fuse portion shown comprises a setting cap 10 which is secured to and is relatively rotatable with respect to the base of the fuse and clockwork train 11. As clearly understood in the art the timing disk 12 is secured to the clockwork train through the spindle 13 and friction disk 14 in order that the timing disk may be rotated on the spindle 13 independently of the clockwork train to position the release shaft slot 15 in the timing disk in any predetermined position of rotatable displacement from the release shaft.

For rotating the timing disk 12 to position the release shaft slot 15 therein a desired distance from the release shaft to correspond with a given setting of the fuse it is usual to employ the setting cap 10 for such purpose and in the instant invention a cantilever setting spring 16 secured

2

at one of its ends by fastening means 17 to the setting cap and having a setting lug 18 in its free end provided with a depending projection 19 adapted to engage in a cooperating perforation 5 in the timing disk is provided. The setting lug 18 above the upper surface of the setting spring is provided with an inclined surface 20 and a centrifugal spring 21 secured to the setting cap at one end, as at 22, is arranged to have its free end portion engage the inclined surface 20 of the setting lug 18 and cam the setting spring 16 down with the depending projection 19 engaged within the cooperating perforation in the timing disk as shown in Fig. 2.

Conveniently the centrifugal spring 21 may be a wire spring with its end 22 formed in a single coil to provide an eye for the cooperating means employed to secure the spring to the setting cap. The free end of the spring is likewise coiled to form an eye within which is secured a centrifugal weight 23.

In the operation of the release mechanism of this invention the parts will normally be disposed as shown in Fig. 2 during the static condition of the fuse. In this position the cantilever setting spring 16 is depressed by interengagement of the centrifugal spring 21 and inclined or beveled surface 20 of setting lug 18 and projection 19 is engaged within the perforation therefor in timing disk 12. When it is desired to set the fuse the cap 10 is rotated a predetermined distance corresponding to the setting desired and this movement of the setting cap transmitted through the attached setting spring 16, lug 18 and projection 19 will rotate the timing disk 12 on the spindle 13 against the friction imposed by the friction disk 14 to displace the release shaft slot 15 the required distance from the release shaft.

After the fuse is set and when it is fired from a gun attached to a projectile the rotation imparted to the projectile will develop centrifugal force which will act on the weight 23 attached to the free end of the centrifugal spring 21 to displace the latter outward from engagement with the bevel 20 of setting lug 18. Outward movement of the free end of the centrifugal spring will permit the setting spring 16 to recover its unstressed position shown in Fig. 3 removing

the projection 19 from interlocking relation with the timing disk 12. The timing disk is now free to be driven by the clockwork train through the spindle 13 and friction disk 14 and will be driven through a distance corresponding to the time 55 for which the fuse is set whereupon the re-

lease shaft slot 15 will be brought to a position where the release shaft may enter the same and release the firing pin to ignite the detonating train of the fuse.

Having now described what is at present a preferred embodiment of the invention, I claim and desire to secure by U. S. Letters Patent:

1. In a fuse of the type having a timing disk in combination, a setting cap for enclosing the timing disk and rotatable relative thereto, a setting spring secured to the setting cap having a free end portion provided with means adapted to be interlocked with the timing disk upon depression of the setting spring and spring means secured to said setting cap normally depressing the setting spring, said last named means being operable by centrifugal force to release the setting spring from its depressed position. 15

2. In a fuse of the type having a timing disk in combination, a setting cap for enclosing the timing disk and rotatable relative thereto, a cantilever setting spring secured to the setting cap, a setting lug having a beveled upper surface and

depending projection secured to the free end of the setting spring, said depending projection adapted to be interlocked with the timing disk upon depression of the setting spring, a centrifugal spring provided with a weight on one end secured to the setting cap through its end remote from the weight and being biased to normally engage the beveled surface of the setting lug adjacent its weighted end portion to depress the setting spring with said projection interlocked with the timing disk, said weighted end portion of the centrifugal spring being operable by centrifugal force to be disengaged from the beveled surface of the setting lug.
